UNITED STATES PATENT OFFICE.

CHARLES M. FORD, OF CASTALIA, OHIO.

SLED-RUNNER.

No. 909,775.

Specification of Letters Patent.

Patented Jan. 12, 1909.

Application filed May 9, 1907. Serial No. 372,761.

To all whom it may concern:

Be it known that I, CHARLES M. FORD, citizen of the United States, residing at Castalia, in the county of Erie and State of Ohio, have invented certain new and useful 5 Improvements in Sled-Runners, of which the following is a specification.

My invention relates to improvements in sled construction and has special reference 10 to the formation of the runners and knees.

The chief objects of my invention are to provide a sled runner the main portion of which can be formed of a single piece, preferably of sheet steel, so as to produce a 15 structure of light weight and yet having the requisites of lightness, economy of construction, simplicity and strength.

Other objects of my invention are to supply supporting knees of improved construction that will give the required strength 20 with a minimum of weight and to enable the parts to be assembled with little labor and with the use of ordinary tools.

A further advantage lies in the opportunity to use short pieces of timber for filling purposes thus economizing the material.

I accomplish the above and other minor objects by the use of the appliance illustrated in the accompanying drawing which forms 30 a part of this specification and in which:—

Figure 1 is a side view of a bob sled embodying my improvements; Fig. 2 is a sectional view on the line 2—2 of Fig. 1, and Fig. 3 is a rear elevation of a single runner.

Referring to the drawing in detail, the 35 numeral 3 indicates the side bars and 4 the cross-beams of a bob sled as ordinarily constructed. The said cross beams are supported upon knees 5, each knee being preferably formed of a single piece of sheet steel bent into channel form as shown in Fig. 2, the side plates of the channel being bent outwardly at the upper end to form flanges 6 which are secured to the cross beams 4 by 40 bolts 7. The main portion 8 of the runner is formed of a single plate of sheet steel bent into channel form and furnished with the usual forward curve 9. The sides of the channel are cut away beyond the curve 9 45 to form a tongue 10 which is bent back over the frame and is secured to the upper face of the side bar 3 by a bolt 11. The knees 5 are adapted to be inserted between the sides of the channeled runner 8 and are se-

cured thereto in a substantial manner by 55 bolts or rivets 12.

Since the open side of the channel of the runner is uppermost and therefore liable to become filled with snow and ice or other foreign substances which would render it 60 unsightly I provide a filling 13 of any suitable material pieces of wood being usually the most desirable for that purpose, and as the lengths will be comparatively short there will be an economy in the materials used. 65 Besides preventing the accumulation of dirt this filling will give a finish to the member and also add to the strength of the channel by furnishing a backing for the channel steel which is made as light as will be consistent 70 with the needed strength. For this reason it is necessary to reinforce the under surface of the runner with a shoe 14 which is preferably made of cast iron or similar metal of sufficient thickness to withstand the frictional wear. This shoe 14 may be secured in any desired manner to the face of the runner, a very convenient method being the employment of screws 15 inserted in countersunk holes in the face of the shoe and penetrating the channel steel to engage the wood 75 backing 13, thus serving the double purpose of securing the shoe and backing in position.

While I have shown my improved sled runner construction as applied to bob sleds 80 it is evident that the device is equally applicable to sleighs or sleds of any description and I do not wish, therefore, to be limited to the precise form set forth.

Having thus described my invention what 90 I claim as new, is—

In a sled, the combination with a frame composed of side and cross-pieces, of channel runners secured at their front end to said frame, channel knees connecting the runners 95 and frame, each knee consisting of a single channel-bar secured to the runner channel bar at its lower end, and having its sides bent laterally at the upper end to form flanges, said flanges secured to both frame 100 side and cross pieces, and filling pieces for the channel runner.

In testimony whereof I affix my signature in the presence of two witnesses.

CHARLES M. FORD.
